UNITED STATES PATENT OFFICE.

RALPH H. PAULEY, OF SEWICKLEY, PENNSYLVANIA.

TICKET-CABINET.

1,046,488.

Specification of Letters Patent.

Patented Dec. 10, 1912.

Application filed March 2, 1912. Serial No. 681,219.

To all whom it may concern:

Be it known that I, RALPH H. PAULEY, residing at Sewickley, in the county of Allegheny and State of Pennsylvania, a citizen 5 of the United States, have invented or discovered certain new and useful Improvements in Ticket-Cabinets, of which improvements the following is a specification.

My invention relates to ticket cabinets, 10 and is particularly well adapted for use in large railroad ticket offices, wherein a large number of coupon tickets of different sizes must be kept on hand, and wherein economy of space is essential.

15 The object of my invention is to provide a ticket cabinet, each compartment or pigeon-hole of which may be adjusted in width, depth, and height, according to the requirements of service.

20 My invention is illustrated in the accompanying drawing, which forms part of my specification, and in which—

Figure 1 is a perspective view of a portion of a ticket cabinet embodying my invention; 25 Fig. 2 is a perspective view of a depth-adjusting abutment; and Fig. 3 is a perspective view of the back of a destination card holder, adapted to be used in connection with the cabinet shown in Fig. 1.

30 The cabinet shown in Fig. 1 is but the bottom portion of a unit section of the complete cabinet. Each unit section preferably consists of a box-like casing 1, shelves 2, and partitions 3; and each of the said several parts are preferably formed of sheet metal. The casing 1 preferably has side 35 walls 4 and a bottom portion consisting of a flat sheet 5 and a corrugated sheet 6, so formed as to provide grooves 7, extending 40 from the front to the rear of the cabinet. The corrugated sheet 6 may be secured in any desired manner to the flat sheet 5 or it may be laid loosely thereon. Similarly, each successive shelf 2 preferably consists of a 45 flat sheet 8 and a corrugated sheet 6 on the top and the bottom thereof, the several sheets being united or not, as desired; and each successive shelf 2 may be supported by the partitions 3, the ends of which are adapted 50 to fit into the grooves 7. To the end that there may be any desired distance between the shelves, the partitions may be made of a series of different widths. Also, as an additional support for the shelves, I preferably 55 provide end supports 9, as shown.

As will be seen from the foregoing description, each section of the cabinet may be made up of a series of shelves 2, any desired distance apart, the shelves being supported by the partitions 3 and supports 8. Also the 60 space between each shelf may be divided into any desired number of compartments of a suitable size to hold the particular tickets intended to be kept therein. And it will be seen that a readjustment of the size of each 65 compartment as well as the distance between the shelves may be easily made at any desired time.

To the end that the tickets in each compartment may be held in their proper position, which is substantially flush with the front of the cabinet, I provide an abutment 70 10, preferably formed a spring adapted to be placed in the grooves 7 and to press yielding against the adjacent sides of the successive shelves 2. Such an abutment is shown in position between the upper two shelves at the rear of the tickets 11, and it will be understood that such an abutment 75 may be placed at any desired distance from 80 the front of the cabinet.

As a part of the complete cabinet I also provide a card holder, adapted to hold a card giving the destination of tickets kept in a particular compartment, and further 85 adapted to be easily secured in any desired place in the cabinet. My preferred form of destination card holder, and that adapted to be used in connection with the specific disclosure shown herein, is best illustrated in 90 Fig. 3; and consists of a card receiving portion 12, having a series of projections 13 on the back thereof, so shaped and disposed as to fit into the top and bottom grooves of each shelf 2. Such a card holder facilitates 95 the readjustment of the ticket cabinet, as will be readily understood.

I do not wish to limit myself to the details of construction, shown herein, for obviously many changes may be made by those skilled 100 in the art without departing from the spirit of my invention.

I claim as my invention:

1. In a ticket cabinet, the combination of a casing, a series of shelves placed one above 105 the other and having their upper and lower surfaces provided with grooves, and vertically disposed partitions engaging adjacent faces of the said shelves and forming laterally adjustable compartments between the 110

said shelves, the said partitions affording supports for the successive shelves, substantially as described.

2. In a ticket cabinet, the combination of 5 a casing, a series of groove-provided shelves placed one above the other, vertically disposed partitions engaging adjacent faces of the said shelves and forming compartments

therewith, and an adjustable abutment engaging said grooves.

In testimony whereof I have hereunto set my hand.

RALPH H. PAULEY.
